United States Patent Office.

WILLIAM O. LESLIE, OF PHILADELPHIA, PENNSYLVANIA.

Letters Patent No. 79,362, dated June 30, 1868.

IMPROVED BRICK-MACHINE.

The Schedule referred to in these Letters Patent and making part of the same.

TO ALL WHOM IT MAY CONCERN:

Be it known that I, WILLIAM O. LESLIE, of Philadelphia, in the county of Philadelphia, and State of Pennsylvania, have invented certain new and useful Improvements in Brick-Machines; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention relates to brick-machines of that class in which a horizontally-rotating wheel, having a series of moulds in it, is used; and the invention consists of certain novel devices for feeding the prepared clay from the hopper to the moulds, and in a novel arrangement of devices for pressing the clay into the moulds, as will be hereinafter explained.

Figure 1 represents a side elevation of the machine, with a portion of the hopper broken away, to show the internal arrangement.

Figure 2 is a side elevation of a portion taken from a side at right angles to fig. 1, and also having a portion shown in section.

In constructing my improved machine, I prepare a suitable frame, as represented in fig. 1, and mount therein a rotating mould-wheel, G, of the usual construction, the moulds being provided with followers, r, as shown in fig. 2, which are raised by an inclined circular track, H, as usual in this class of machines. At one side of the machine, upon a vertical frame, I mount a hopper, A, having placed transversely therein a couple of smooth iron rollers, B, for crushing the clay, there being located directly under these another roller, C, provided with projecting arms or pins, for mixing and working the clay. These parts being shown in fig. 1.

The lower portion of the hopper is inclined as shown in fig. 1, its sides being made converging, and in the bottom is placed a spiral screw, E, for forcing the clay through a short horizontal spout or mouth-piece, F, into a rectangular box, I, so located that the moulds u are brought successively under it as the mould-wheel rotates, and as shown more clearly in fig. 2, there being a gate or slide, b, located at the side of the box I, as shown in fig. 1, to regulate the passage of the clay into the box I from the hopper.

In the box I is placed a plunger, R, arranged to move vertically in suitable guides, as shown more clearly in fig. 2. To operate this plunger, I provide a cam-wheel, K, which is secured upon a shaft, J, this cam engaging with the plunger R, and imparting to it an intermittent reciprocating movement.

Upon the mould-wheel G is placed a plate, P, which extends from the rear side of the hopper, at its lower portion, past the box I, for some distance out over the moulds, in the wheel, as shown in fig. 1. The clay, as it is forced out of the hopper by the screw E, passes along on top of this plate P, through the spout F, into the box I, where there is a hole made through the plate P, through which the clay enters the mould u, being forced therein by the plunger R, as shown in fig. 2. A short distance beyond this point another opening is made in the plate P, directly in the line of passage of the moulds; and to the plate at this point is secured a scraper, a, set inclined, with its lower edge coming in close contact with the upper surface of the mould-wheel, so as to slice or pare off any surplus of clay that there may be projecting above the surface of the wheel, as shown in fig. 1. The plate P extends beyond the scraper a for some little distance, so that as the follower r begins to rise, by coming at this point in contact with the incline on the track H, the clay in the mould is pressed upward against the under face of plate P, by which the brick in the mould is further compressed, and at the same time smoothed on its upper face, by rubbing against the smooth surface of the plate.

A pulley, L, is placed on the axis of one of the grinding-rolls, B, both of which are provided with gear-wheels, d, at their opposite ends, which engage with each other, and one of which also gears into a similar wheel, f, on the mixing-roller C. On the opposite end of this roller C is a bevel-gear, n, which engages with a corresponding gear, o, on the shaft of the feeding-screw, E, by which motion is in turn imparted to it also. On the end of the shaft of one of the grinding-rolls, B, outside of the spur-gear d, is secured a bevel-gear, h, which

engages with a corresponding wheel, *l*, on the cam-shaft *J*, which also has on its lower portion a pinion, *p*, which engages with teeth on the periphery of the mould-wheel *G*. By this arrangement of gearing it will be seen that when the pulley *L* is rotated, motion will be imparted simultaneously to all other portions of the machine. If it be desired to operate the machine by horse-power, a sweep may be secured to the top of shaft *J*, as represented by *T* in fig. 1, in which case the shaft *J* becomes the driving-shaft.

The operation will be readily understood from the foregoing description, and need not be, therefore, further described. It will of course be understood that the motion of the plunger *R* is to be so regulated as to descend at the instant the mould comes under the box *I*, so as to force the clay from the box *I* into the empty mould underneath.

By this arrangement of devices I am enabled to produce a machine that operates with rapidity, and that will produce a very superior quality of bricks.

Having thus described my invention, what I claim, is—

1. The combination of the hopper having the inclined bottom, with the screw *E* located therein, with the spout *F* and box *I*, all constructed and arranged to operate substantially as shown and described.

2. In combination with the box *I*, I claim the plunger *R* and shaft *J*, having the cam *K* and wheel *P* mounted thereon, for rotating the mould-wheel continuously, and operating the plunger intermittently, substantially as herein described.

WM. O. LESLIE.
